UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

TURBINE-WHEEL CONSTRUCTION.

SPECIFICATION forming part of Letters Patent No. 781,022, dated January 31, 1905.

Application filed July 22, 1904. Serial No. 217,677.

To all whom it may concern:

Be it known that I, RICHARD H. RICE, a citizen of the United States, residing at Lynn, county of Essex, State of Massachusetts, have 5 invented certain new and useful Improvements in Turbine - Wheel Constructions, of which the following is a specification.

It has been demonstrated that large wheels as commonly constructed and used in elastic- 10 fluid turbines have a tendency to warp or change their shape, due to unequal temperatures on opposite sides. As a rule the inlet side of the wheel expands to a greater extent than the exhaust side, and this frequently causes rubbing between the relatively 15 rotating parts.

The object of my invention is to provide a wheel of improved construction wherein the temperature effects can be disregarded wholly 20 or at least in large part.

In carrying out my invention a composite wheel is provided comprising a central portion, which is of rugged construction, and detachable portions, which are suitably attached to the central portion. The central and detachable portions are so united that they are capable of having a slight movement 25 with respect to each other in a radial direction, the object of this being to permit one portion to expand or contract without affecting another portion or portions. In this connection it is to be noted that the changes in the wheel due to temperature changes are small; but if not compensated for it either 30 means large clearances resulting in excessive leakage, especially where the pressure of the fluid stream is above that of the casing, or rubbing between relatively rotating parts. The central portion may be constructed to 35 carry all of the buckets, while the detachable portion or portions, as the case may be, act as protecting devices only. On the other hand, the detachable portions may each carry one or more rows of buckets. I may use 40 either or both constructions in the same turbine, or I may make a wheel with one detachable portion carrying buckets, while the other or others are plain. In the construction specified the main portion of the wheel is pro-

tected to a large degree from temperature 50 changes by the other portion or portions; but to further protect the wheel dead-air chambers are provided which are located between the main body of the wheel and the detachable portion or portions. In addition to protecting 55 the wheel from temperature changes the detachable portions also serve to strengthen it.

In the accompanying drawings, which illustrate embodiments of my invention, Figure 1 is a partial view in elevation and section of 60 an elastic-fluid turbine of the Curtis type. Fig. 2 is a partial plan view of the same with certain of the parts broken away for the purpose of illustration. Fig. 3 is a detail view in section, showing a slight modification; and Fig. 4 is an enlarged view showing the means 65 for attaching the covering to the main body of the wheel.

1 represents a wheel-shaft that is vertically disposed and suitably retained by bearings 70 inside of the casing 2. Situated above the casing 2 and bolted thereto is a casing 3, which carries intermediate buckets 4 and a sectionalized expanding-nozzle 5. It may or may not carry valves for regulating the admission of 75 fluid to the sections of the nozzle.

6 represents the main body of a wheel which is taper-bored to receive the shaft 1. At the periphery the body is provided with one or more rows of buckets 7, which rotate with respect to the intermediate buckets 4. The main body of the wheel is provided with projections 8, which receive the covering 9, the latter being preferably made of rolled-steel plate. The periphery of the plate or covering is provided 80 with one or more rows of buckets 10, which receive steam or other elastic fluid directly from the nozzle 5. The covering is secured in place by bolts 11 and 12, and between the body of the bolt and the covering is a small 85 clearance, so that the covering can expand and contract without disturbing the main body portion of the wheel. Between each of the coverings and the main body are one or more chambers 13, which may be filled with air, or, 90 if desired, with motive fluid in a more or less expanded state. In the present illustration the concentric projections 8 divide the space 95

between the web of the wheel and the covering into three concentric chambers; but this may be otherwise arranged, if desired. The principal thing is to have chambers in the 5 wheels that are interposed between the covering and the main body portion to prevent the free transfer of heat. I may admit steam or other heated fluid into the chambers to act as a compensating means.

10 Referring to Fig. 3, I have shown a slight modification wherein the main body portion 14 carries all of the wheel-buckets 15. The opposite sides of the wheel are provided with coverings 16 in the form of steel plates, which 15 are secured to the projections 17 on the wheel by bolts 18. These bolts permit the covering to expand and contract slightly with respect to the wheel, without, however, causing the latter to be distorted. 19 represents the nozzle, which supplies fluid to the wheel and may 20 be expanding or non-expanding in character. 20 represents the intermediate buckets, which are situated between the wheel-buckets and are supported by the casing 21. The outside 25 of the casing is provided with a covering 22, of non-conducting material, to prevent the radiation of heat.

In Fig. 4 I have shown one of the means which may be employed for securing the covering to the main body of the wheel. 23 represents the main body of the bolt, which passes through a hole in the covering or plate 9, which is slightly larger in diameter, so that a limited amount of clearance is provided. The head 35 of the bolt is preferably countersunk to reduce the rotation losses. The covering, in addition to protecting the main body of the wheel from the hot steam or other motive fluid, also serves to strengthen it.

40 In accordance with the provisions of the patent statutes I have described the principle of operation of my invention, together with the apparatus which I now consider to represent the best embodiment thereof; but I desire 45 to have it understood that the apparatus shown is only illustrative and that the invention can be carried out by other means.

What I claim as new, and desire to secure by Letters Patent of the United States, is—
50 1. A turbine-wheel comprising a number of separate portions, with means for securing said portions together which permit them to expand and contract individually.

2. A turbine-wheel comprising a number of 55 separate portions, with bolts extending parallel with the axis for securing said portions to-

gether which permit them to expand and contract individually.

3. A turbine-wheel comprising a main body portion, buckets carried thereby, a covering 60 which protects the main body from the effects of the motive fluid, and means for securing the covering in place, which permit the covering to expand and contract without distorting the main body portion. 65

4. A turbine-wheel comprising a main body portion, buckets carried thereby, a covering on each side of the main body for protecting it from temperature changes, and means for securing the coverings to the main body and 70 at the same time permitting them to expand and contract without affecting said body.

5. A turbine-wheel comprising a main body portion, projections thereon, a covering for the body portion which engages the projections, a chamber between the body and the covering, and attaching means for the covering which permit it to expand and contract without 75 affecting the body portion.

6. A turbine-wheel comprising a main body portion, a covering for the side thereof, a chamber formed between the side and the covering, and means for attaching the covering to the body portion, which permit it to expand and contract without affecting the body 80 portion.

7. A turbine-wheel comprising a main body portion, a covering therefor, buckets carried by the covering, and means for attaching the covering to the body, which permit it to expand and contract without affecting the body. 90

8. A turbine-wheel comprising a body portion, a covering for the body, buckets carried thereby, and bolts for attaching the covering to the body, which permit the two to have 95 slight relative movements to compensate for differences in expansion.

9. A turbine-wheel comprising a main body portion, projections thereon, buckets attached to the body, plates located on opposite sides 100 of the body, which engage the projections, chambers formed between the plates and body, and attaching devices which enter the projections and hold the plates in place but permit them to expand and contract independently 105 of the main body.

In witness whereof I have hereunto set my hand this 20th day of July, 1904.

RICHARD H. RICE.
